WINDOW-ACTUATING MECHANISM

Barton H. Noland, New York, N. Y., and Edmund
L. R. Smith, Baltimore, Md.

Application January 5, 1939, Serial No. 249,364

5 Claims. (Cl. 268—123)

Our present invention relates generally to window-actuating mechanism, and has particular reference to that type of arrangement which permits a window to be automatically adjusted under predetermined conditions.

While our invention is not restricted to any particular mode of use, the present mechanism is well adapted for application to a household window which is intended to be restored from an open condition to a normally closed condition at a predetermined time or under predetermined circumstances. We have herein illustrated our new mechanism in association with such a window, for the accomplishment of such a purpose; but it will be understood that it is equally within the purview of our invention to control the operation of any other type of window or closure, such as a door or transom. In fact, certain phases of our invention are applicable to the automatic control of any two relatively movable elements whose relationship is comparable to that of a window and window frame, a door and door frame or the like.

Furthermore, where the invention is applied to a window or similar closure, the automatic action need not always serve to restore the closure to a normally shut condition. For example, under certain circumstances it might be desirable to employ our invention for the purpose of opening a window or closure at a predetermined time or under predetermined circumstances; or to adjust such window or closure in some other manner.

The general object of the invention is to provide a mechanism which is simple in structural nature, inexpensive to manufacture, easy to install, and efficient and reliable in operation. At the same time, we have aimed to provide a mechanism which is compact and relatively inconspicuous, and devoid of unsightly features.

Our present mechanism is characterized by a telescopic assembly of relatively movable tubular elements one of which is secured to the window, the other to the window frame, an actuating means such as a spring being accommodated within said assembly in operative interposition between the tubular elements. Where the invention is applied to the ordinary sliding type of window, it is preferable to use two such telescopic assemblies, one on each side of the window.

It is a further object of our invention to provide an arrangement which permits the window to be releasably locked in any selected adjusted position, other than the normal position. Thus, if the invention is employed for the purpose of

restoring a window to a normally shut condition, it is possible freely to open the window to any desired extent and to lock it in a releasable manner at any selected open position. The locking means is preferably of a character which prevents access from the exterior of the window.

Another object of our invention is to provide an improved releasing means, capable of control from a relatively remote point, e. g., by means of an alarm clock or the like. The releasing means is electrically controlled, for example, by means of an electromagnet, and it is a particular feature of our invention to provide certain improvements in the electric circuit, whereby the functioning of the mechanism is rendered safe, economical, and reliable.

It is a further object of our invention to provide a new type of control for the releasing means, viz., a control which responds to rain or its equivalent. This control, which may be said to be a type of electric relay, embodies features of novelty which make it independently useful for a wide variety of other purposes; although its employment with a window-actuating mechanism is peculiarly appropriate and useful.

The improved relay comprises a normally ineffective means which is adapted to be rendered effective by rain or its equivalent, and includes an element which is electrically non-conductive when dry but which becomes conductive when wet.

We achieve the foregoing objects, and such other objects as may hereinafter appear or be pointed out, in the manner illustratively exemplified in the accompanying drawings, in which—

Figure 1 is a front elevational view of a conventional type of sliding household window, with our mechanism associated therewith, the window being shown closed;

Figure 2 is a view similar to Figure 1 showing the window in an adjusted open position;

Figure 3 is an enlarged cross-sectional view through a telescopic assembly of the present character, this view being taken substantially along the line 3—3 of Figure 1;

Figure 4 is a view taken from the left of Figure 3, this view being thus an enlarged view of the left hand portion of Figure 1 taken in the same direction as Figure 1;

Figure 5 is an enlarged plan view taken substantially along the line 5—5 of Figure 4;

Figure 6 is an enlarged plan view taken substantially along the line 6—6 of Figure 4;

Figure 7 is an enlarged cross-sectional view

showing the locking and releasing means, this view being taken in the direction 7-7 of Figure 2;

5 Figure 8 is a cross-sectional view taken substantially along the line 8-8 of Figure 7;

Figure 9 is a cross-sectional view taken substantially along the line 9-9 of Figure 7;

Figure 10 is a diagrammatic view showing the electrical circuit;

10 Figure 11 is a plan view of the special rain-responsive control device;

Figure 12 is a cross-sectional view taken substantially along the line 12-12 of Figure 11; and

15 Figure 13 is a cross-sectional view taken substantially along the line 13-13 of Figure 11.

We have chosen to illustrate our invention in association with the lower sash 20 of a conventional window which includes the window frame 21 and the upper sash 22; and we have 20 illustratively shown an installation intended to restore the window 20, when the mechanism functions, to the normally shut condition shown in Figure 1.

25 We have also shown the preferred use of two telescopic assemblies 23 and 24, each of which is secured to the upper portion of the window 20 by means of a bracket 25, and to the lower portion of the window frame 21 by means of a bracket 26.

30 Only a single locking and releasing means is needed, and this is designated by the general reference numeral 27 and is shown in association with the telescopic assembly 24.

In Figure 5 we have illustrated one of the 35 brackets 25, and in Figure 6 we have illustrated one of the brackets 26.

The bracket 25 is secured to the window 20 by means of screws or fasteners 28, and comprises a U-shaped element 29 carrying the spaced but aligned pivots 30. The inner ends of these pivots are preferably in screw-threaded engagement with the opposed U-shaped clamps 31 adapted to be tightened together by the studs 32. The clamps 31 conjointly engage securely and permanently around the upper portion of the telescopic assembly, which is thus pivoted at its upper end about a pivot axis perpendicular to the longitudinal axis of the telescopic assembly.

The bracket 26 is fastened to the window frame 21 by means of screws or fasteners 33 and comprises a U-shaped element 34 provided with the spaced but aligned pivots 35. These pivots engage with the opposed U-shaped clamps 36 adapted to be tightened together by the studs 37. The clamps 36 conjointly engage securely around the lower end of the telescopic assembly, and the pivot axis is parallel to the pivot axis at the upper end of the assembly.

These pivot axes facilitate the installation of 60 the telescopic assembly, maintaining its parts in true slidable alignment; and the adjustability afforded by the screw-threaded elements 30 is of further aid in installing the mechanism in correct fashion.

65 The telescopic assembly 23 is illustrated most clearly in Figure 3, and it will be understood that the assembly 24 is of identical character.

The assembly consists of relatively movable tubular elements the upper one of which is secured to the window 20 by means of the bracket 25. This element has an end block 38 which carries two concentric tubes, an inner tube 39 and an outer tube 40.

70 The other element of the assembly is secured 75 to the window frame 21 by the bracket 26, and

may have an end block 41 which also carries two concentric tubes, an inner tube 42 and an outer tube 43.

The inner tubes 39 and 42 constitute a snugly fitting pair, and outer tubes 40 and 43 constitute a similar snugly fitting pair. In the annular space between these pairs is an actuating means which we have shown in the form of a coiled spring 44 coaxial with the telescopic assembly as a whole. The upper end of the spring is secured 10 at 45 to the block 38, and the lower end of the spring is secured as at 46 to the block 41.

The innermost tube 39 is provided with a closed end block 47, to which a leather skirt 48 is preferably attached, so that the tube 39 cooperates with 15 the tube 42 in the nature of a plunger and cylinder. To facilitate this operation the block 41 is preferably provided with the longitudinal vent 49 in which a valve member 50 is loosely mounted.

When the window is moved into an open position, the tube 39 slides upwardly within the tube 42, and the tube 40 slides upwardly within the tube 43. Air is permitted to enter through the vent 49. During this movement, the spring 44 becomes tensioned.

Accordingly, in order to maintain the window in an open position, it must be locked in some way; and when it is released, the spring 44 draws the two tubular elements back to their normal relationship shown in Figure 3. During this 30 movement, a pressure is developed, beneath the plunger element 48, which serves to retard the action during its final stages. There is sufficient leakage around the valve 50, and through the other joints, to permit the compressed air to 35 escape.

For the purpose of locking the elements in any selected adjusted relationship, with the spring tensioned, we provide the upper end of the tube 43 with one or more slits 51 (see Figure 7), and 40 we provide a releasable clamp 52 which engages around this slotted portion. When the clamp is tightened the tubes 43 and 40 are securely clamped together against relative movement; and when the clamp 52 is loosened, the normal 45 movability is restored.

The operation of the locking means, i. e., the clamp 52, and the operation of the releasing means, is most clearly illustrated in Figures 7-10.

The clamp 52 is in the form of a resilient band 50 whose two ends 53 are brought into parallel spaced relation. One of them carries a lug 54 having an inclined cam surface. A pin 55 extends through both ends 53, and is provided with an enlargement 56, and also with a cam 57 which 55 cooperates with the cam 54 when the pin 55 is given a rotative movement.

This movement of the pin is effected by a manually operable element 58 which swings between the full-line and the dot-and-dash line 60 positions of Figure 7. When this element is in the full-line position the clamp 52 is tightened. When it is in the dot-and-dash position the clamp 52 is loosened.

A tension spring 59, or its equivalent, tends to 65 draw the element 58 normally into the dot-and-dash position, and when this element is moved up into the full-line position, a projection 60 latches itself behind a lever 61 pivoted at 62 and normally held in the full-line position of Figure 8 by 70 means of a spring 63 or its equivalent (see Figure 9).

The lever 61 carries an armature 64 which is subject to the influence of an electromagnet 65, so that when the magnet is energized the lever 61 75

is pulled into the dot-and-dash position of Figure 8, thereby releasing the element 58, and allowing the spring 59 to pull the element 58 into the dot-and-dash position of Figure 7.

The electromagnet 65 may be of any suitable or convenient character, or may be replaced by an equivalent electrical instrumentality. It is arranged in an electric circuit which includes a switch 66. This switch has been shown by us in the form of a double pole knife switch, the movable element 67 being pivoted at 68 and having a handle 69 arranged in the path of movement of the element 58. The latter also carries a finger 70 which is adapted to engage the handle 69 during the downward movement of the element 58.

The adjustable portion of the locking means 52, the manually operable element 58, the releasing means including the magnet 65 and the lever 61, and the switch 66, are preferably mounted as a unit in a box 71 which is permanently clamped to the tube 43 by clamps 72. The box 71 has a slot 73 through which the free end of the element 58 projects, so that it is readily accessible.

The electric circuit, as shown most clearly in Figure 10, is quite simple and includes the ordinary supply line 74, the switch 67, the electromagnet 65, and a suitable control 75 which may be of any desired character and which consists essentially of a normally open switch or relay 76 adapted to be closed at a predetermined time (e. g., by means of an alarm clock mechanism) or under predetermined circumstances.

The operation of the control 76, however, has no effect upon the circuit unless the switch 67 is closed, and it will be observed that this switch is never closed unless the element 58 is in a position which renders the locking means operative. In this way, the installation is entirely safe, no current is ever wasted, and the electric circuit is not capable of functioning at all, except when the device is "set" by adjusting the free end of the element 58 into the locking position.

The operation of the mechanism will be clear from the description hereinbefore given. Under normal circumstances, the window remains in its normal shut position. At any time, it may be opened to any desired extent and retained or locked in this adjusted position by merely moving the element 58 into the locking position. If the window is thereafter to be shut, or readjusted, nothing more is needed than to momentarily release the element 58 (which may be done by hand if desired). If the restoration of the window to its normal position is to be automatically effected, the control device is properly set, and at a predetermined time, or under predetermined circumstances, the electric circuit will be closed automatically, thereby energizing the magnet 65, releasing the locking means, and allowing the actuating means, such as the spring 44, to restore the window to its normal position.

This "normal position" need not necessarily be a "shut" position, as hereinbefore stated. Furthermore, the mechanism need not necessarily be associated with a slidable window, but may with equal facility be installed in association with a pivoted window or closure such as a door, transom, or casement window. The terms "window" and "window frame," as used herein and in the appended claims, are therefore intended to include within their significance any relatively movable pair of structural elements comparable to a window and its window frame.

The two pairs of slidable tubes, entering into

the construction of the present telescopic assembly, afford a staunch and smoothly-operating construction which is unusually reliable and effective. These pairs of tubes also provide a convenient annular space between them to accommodate and thereby conceal the actuating means. And, as herein described, the inner pair of tubes lends itself readily to a plunger and cylinder cooperation which is effective and useful in assuring smooth and unhurried operation of the 10 device.

The special control device which forms a part of our present invention, but which is obviously of independent utility in a wide variety of fields, is illustrated most clearly in Figures 11-13. We have illustratively shown a receptacle 77 within which two spaced electric terminals 78 are mounted in insulated relation from each other. With this object in view, these terminals may be mounted on insulation, or otherwise electrically 20 separated in any convenient manner. Arranged in bridging relation to these terminals is an element 79 which we have shown in the form of a small cylinder. This element is arranged below an opening 80 in the receptacle, so that drops of 25 rain, or their equivalent, may fall through and encounter the element 79.

The element 79 is of a material which is electrically non-conductive when dry, but which is adapted to become conductive when wet. Rock 30 salt embodies these characteristics, and the element 79 may therefore be a block or element of rock salt.

The entire device is preferably associated with lead wires 81 which extend to the terminals 78 35 respectively, and at the end of these lead wires there is preferably arranged a separable connector 82 permitting this entire control device to be separably associated with the electric circuit, as indicated in Figures 1 and 2.

When this device is used with a window-actuating mechanism, the receptacle 77 is placed on the window sill, or is in some other way exposed to the weather, but preferably not entirely outside. As a result, the window may be locked in 45 an open condition, as shown in Figure 2, without fear of having rain, snow or sleet, enter through the window; because as soon as any such inclemency results in the ingress into the receptacle 77 of rain or its equivalent, the control device becomes operative to energize the electromagnet 65 and thereby bring about closure of the window.

It will be understood that the receptacle 77 may be made of any suitable material, and that 55 its shape may be varied and modified to suit requirements.

In general, it will be understood that changes in the details, herein described and illustrated for the purposes of explaining the nature of our invention, may be made by those skilled in the art without departing from the spirit and scope of the invention as expressed in the appended claims. It is, therefore, intended that these details be interpreted as illustrative, and not in a 60 65 limiting sense.

Having thus described the invention and illustrated its use, what we claim as new and desire to secure by Letters Patent is—

1. In a window-actuating mechanism, a telescopic assembly of relatively movable tubular elements one of which is secured to the window, the other to the window frame, each of said tubular elements comprising two concentric tubes, the inner tubes being arranged as a snugly fit- 70 75

- ting inner pair, the outer tubes being arranged as a snugly fitting outer pair, and actuating means arranged in the annular space between said pairs and operatively interposed between said tubular elements.
6. 2. In a window-actuating mechanism, a telescopic assembly of relatively movable tubular elements one of which is secured to the window, the other to the window frame, each of said tubular elements comprising two concentric tubes, the inner tubes being arranged as a snugly fitting inner pair, the outer tubes being arranged as a snugly fitting outer pair, and actuating means arranged in the annular space between said pairs and operatively interposed between said tubular elements, said actuating means comprising a coiled spring coaxial with said tubular elements.
10. 3. In a window-actuating mechanism, a telescopic assembly of relatively movable tubular elements one of which is secured to the window, the other to the window frame, each of said tubular elements comprising two concentric tubes, the inner tubes being arranged as a snugly fitting inner pair, the outer tubes being arranged as a snugly fitting outer pair, and the tubes of one of said pairs being constructed to cooperate as a plunger and cylinder.
15. 4. In a window-actuating mechanism, a tele-
- scopic assembly of relatively movable tubular elements one of which is secured to the window, the other to the window frame, each of said tubular elements comprising two concentric tubes, the inner tubes being arranged as a snugly fitting inner pair, the outer tubes being arranged as a snugly fitting outer pair, the innermost tube having a closed end so that it operates as a plunger within the other tube of the inner pair, and actuating means arranged in the annular space between said inner and outer pairs, said actuating means comprising a spring constantly but yieldably urging said tubular element into a normal relationship.
19. 5. In a window-actuating mechanism, a telescopic assembly of relatively movable tubular elements one of which is secured to the window, the other to the window frame, a spring arranged within said assembly to urge said tubular elements constantly but yieldably into a normal relationship, and releasable means for locking said tubular elements in any selected adjusted relationship with the spring tensioned, said releasable means comprising a clamp carried by the window frame and engaging around said tubular elements to clamp them together.
23. 15. BARTON H. NOLAND.
24. 16. EDMUND L. R. SMITH.
